UNITED STATES PATENT OFFICE.

WERNER THIELE, OF ORANIENBAUM, NEAR DESSAU, GERMANY.

MANUFACTURING CIGARS.

Application filed May 14, 1927, Serial No. 191,547, and in Germany May 31, 1926.

This invention refers broadly to the manufacture of cigars, and it is particularly intended to provide means of manufacturing superior grades of cigars by avoiding the difficulties heretofore encountered by providing the cigar with a high grade outer wrapper or cover. In the manufacture of cigars as generally practiced the tobacco is enclosed in the so called cigar-roll comprising the filler and the cover and this roll is then surrounded by the so called wrapping leaf or wrapper. The positioning of the wrapper, which in most cases has to be effected by manual operation, is a very tedious and expensive class of work, requiring a high degree of dexterity and skill; and inasmuch as the wrappers are made from the best and healthiest leaves, any waste occurring in this operation can only be used as a filler and, therefore, cause loss to the manufacturer. Even where application of the wrapper is effected by machinery losses of material in applying the valuable wrapping leaves can not be avoided. Nor has it been possible to simplify and facilitate the operation of applying the wrapper by utilizing the so called tobacco-paper obtained as an artificial product.

These difficulties are overcome by my invention which makes it possible to provide the cigars with a durable but comparatively inexpensive wrapper which may be applied either by machinery or by hand. According to this invention tobacco leaves which, both as regards their color and odor, are suitable for use as wrapping leaves, but which need not be any particularly selected leaves, are very finely subdivided and are suspended in this condition in a liquid containing a suitable combustible binding agent, the more or less pasty material thus obtained being applied to the cigar-roll.

The accompanying drawing is a view partly in elevation and partly in longitudinal section of a cigar having a wrapper produced according to my invention.

As a liquid suitable for the purpose of this invention I may employ, for example, a varnish which will not affect the palatability and the burning of the cigar, such as a solution of a cellulose-ester, preferably the acetyl-ester of cellulose. As a solvent a liquid is used which will readily evaporate and does not have any objectionable influence upon the cigars. The suspended matter comprising the paste of tobacco powder

and applied to the cigar roll produces a firmly adhering, permanent coat upon the roll after the evaporation of the solvent and which will perform the same function as the wrapper heretofore employed. The application of the suspended matter onto the cigar roll may be effected in different ways, either manually or by machinery, for example by the dipping of the cigar roll in the suspended matter or by applying it by sprinkling or painting to the cigar roll.

The cigars produced in accordance with this method will present almost the same appearance as the ordinary cigars provided with wrappers, and they possess the same, and sometimes even a better, taste and are more readily combustible than ordinary cigars. The manufacture is considerably simplified and cheapened; and the very serious losses heretofore incurred in the application of the valuable wrapping leaves are avoided by the employment of the novel kind of covering wrapper.

As a means of suspending the tobacco powder use may be made of solutions of suitable resins or artificial resins or resin-esters. The suspended tobacco material may also be mixed with the well known additions ordinarily employed for the manufacture of cigars to be smoked for the relief of asthma, such as, for instance, the powdered leaves of stramonium or thorn-apple.

It has already been suggested to replace the usual cigarette paper by thin foils obtained from solutions of cellulose esters with the addition of cigarette tobacco. My invention is distinguished from this by providing means of doing away with the employment of natural or artificially prepared special wrappers with the accompanying tedious and very expensive application of the wrapper, which step is not encountered in the manufacture of cigarettes. In accordance with this invention the wrapper is produced directly on the cigar roll itself by the evaporation of the solvent, and this feature and the resulting possibility of manufacturing large quantities of cigars on a manufacturing scale constitutes one of the important objects and advantages of the invention. There is the other important improvement that it is no longer necessary to employ only specially selected valuable wrapping leaves as wrappers since any kind of wrapping leaf which possesses sufficient palatability may be employed. These ad-

vantages are of course not necessary in connection with the manufacture of cigarettes.

The method of treatment herein described is susceptible of being modified and altered 5 in accordance with the convenience of the user and other conditions and different solvents and other materials may be employed without thereby sacrificing the main features of the invention as particularly pointed 10 ed out in the appended claims.

I claim:

1. The method of manufacturing cigars, which consists in suspending tobacco powder in a liquid containing a combustible binding 15 agent and applying the resulting pasty mixture to the core of cigars.

2. The method of manufacturing cigars, which consists in suspending tobacco powder in a mixture of a liquid binding agent 20 with a volatile solvent and applying said mixture to a cigar-core, allowing the solvent to evaporate, and thereby forming a firmly adhering coating of tobacco upon 25 said core.

3. The method of manufacturing cigars, which consists in suspending tobacco pow-

der in a liquid containing a solution of a cellulose ester and applying the mixture obtained to a cigar-core and allowing the applied matter to dry in contact with said core. 30

4. The method of manufacturing cigars, which consists in suspending tobacco powder in a liquid containing cellulose-acetyl-ester, applying the mixture obtained to a cigar-core and allowing the applied matter 35 to dry in contact with said core.

5. As a new article of manufacture a cigar comprising a core and a wrapper formed thereon by a dried and solidified coating of a solution of a cellulose ester and 40 comminuted tobacco leaves incorporated therewith.

6. As a new article of manufacture a cigar comprising a core and a wrapper formed on said core by a dried and solidified 45 solution of a cellulose-acetyl-ester with comminuted tobacco leaves incorporated therewith.

In testimony whereof I have signed my name to this specification.

WERNER THIELE.
